OIL BURNER

Thomas Henry McCauley, Toronto, Ontario,
Canada, assignor of one-half to Morley H.
Breuls, Toronto, Ontario, Canada

Application December 29, 1933, Serial No. 704,457

6 Claims. (Cl. 122—451)

My invention relates to improvements in oil burners, and the object of the invention is to devise an oil burner in which there is no motor or revolving parts, in which the water and oil feed is regulated by a single control, in which the oil when supplied is in proportion with the steam pressure, in which the generator is so formed that the flame is directed thereby towards the sides and back of the fire pot and away from the fire door and so as to provide a maximum heating surface and therefore a maximum evaporating capacity for the water supplied thereto, in which the initial temperature of the generator is maintained by means of a continuous burning pilot, in which a pilot is provided as a heating torch when it is desired to raise the temperature of the generator to convert the water fed thereto into steam, in which the water fed to the generator is preheated during its passage thereto, and in which the water remaining in the generator after the shutting down of the burner is automatically discharged, and it consists essentially of the arrangement and construction of parts as hereinafter more particularly explained.

Fig. 1 is a diagrammatic view of my burner, the gas, water and oil feeds thereto and the means for controlling such feeds.

Fig. 2 is a side elevation of the controlling mechanism.

Fig. 3 is an enlarged sectional detail of the water control valve.

Fig. 4 is a plan view of the combined starter and pressure control chamber on a reduced scale.

Fig. 5 is an inverted plan view of Fig. 4.

Fig. 6 is an enlarged sectional view through the oil feed nozzle body.

In the drawing like letters of reference indicate corresponding parts in each figure.

1 indicates the fire pot of a furnace provided with the grate bars 2 and a stack 3. 4 is a plate resting on the grate bars and formed with a central opening 5. 6 is an air preheating chamber provided with perforations 7 through which air passes into the fire pot. 8 are supporting legs extending upward from the air chamber 6 and on which rests the annular starting and pressure control chamber 9. 10 is a well forming a steam generator depending from the bottom wall of the chamber 9. 11 is a steam outlet located directly above the well 10 and 12 is a steam outlet also formed in the top wall of the chamber 9 but spaced circumferentially from the outlet 11. 9^x is a deflector wall extending between the inner

and outer walls of the chamber 9 between the outlets 11 and 12.

13 is a humidifier supplied with moist steam from the outlet 11 through the tube pipe 11^x. 13^x is a release valve operating on pressure as may be determined to supply humidity. 14 is a nozzle body forming a chamber which is supplied with steam from the outlet 12 through the pipe 12^x after having been dried as it passes from the generator 10 on one side of the wall 9^x around 10 the chamber to the opposite side of such wall to the steam outlet 12. 14^x is a steam nozzle inclined in an upward direction towards the bottom of the chamber 9 at one side thereof. 15 is an oil inlet which extends into the nozzle in 15 a forwardly inclined direction to draw the oil into the steam stream.

The chamber 14 is preferably divided into two portions as shown in Fig. 6 connected together by a transverse bolt 15, and having a strainer dividing the steam inlet and nozzle 14^x. 16 is a panel on which is mounted the feed control mechanism which I will now describe.

I will first describe the water control. 17 is a water supply pipe provided with a shut off valve 17^x and a reducing valve 17° and a strainer 17'. 18 is a preheating chamber located inside the stack 3. The chamber 18 is cylindrical in form, the water pipe 17 extending thereto adjacent the outer end of the preheater. 19 is a water feed pipe extending longitudinally into the chamber 18 to a point adjacent its inner end so that the water is heated as it passes longitudinally thereof from the inlet of the pipe 17 to find outlet through the open end of the pipe 19.

20 is a nipple secured in the panel 16 to which the opposite end of the pipe 19 is secured. 21 is a strainer through which the water passes to the pipe 22. 23 is a T joint in one arm 23^x of which is formed a fine duct 23° at the inner end of which 23' is a valve seat 23'. The other arm 24 of the T is internally threaded to receive the cylindrical valve 24^x which engages at its inner end the seat 23' when in the closed position. The vertical arm 25 is suitably secured in the upper end of a tube 26 carried by a pipe 27 leading through the panel 16 and to the generator 10.

The lower end of the tube 26 is open to provide a water discharge at 26^x when the burner is shut down.

The valve 24^x and the discharge 26^x are alternately opened and closed by mechanism which I will now describe.

28 is a lever secured to the valve 24^x at one end and extending forward through the slot 16^x 55

of the panel 16. 29 is a solenoid carried by the panel 16 and provided with a vertical plunger core 30 having a slot 30^x in its lower end through which the lever 28 extends. 31 and 32 are the main leads of an outside circuit. 33 and 34 are the leads of the inside circuit connected to the leads 31 and 32 by a closing switch 35. 34^x is a controlling thermostat located in the lead 34. The inside circuit is normally open and is closed 10 for operation by the switch enclosed in a casing 36 when the switch 35 is closed and operated by a manually operated lever 36'. The circuits 33, 34, when closed energize the solenoid 29 and when energized raise the lever 28 to open the 15 valve 24^x permitting water to flow through the tube 26 and pipe 27 to the generator 10.

The discharge is held closed by a closure 37 carried on a link wire 38 secured at its upper end to a rod 39 hung at its upper end on the lever 28. 20 The rod 39 is tubular to receive the upper end of the wire 38 which is adjustably secured therein by a set screw 40.

The wire 38 is bent intermediately of its length into a spring loop 38^x which, when sprung open 25 by the raising of the lever 28 on opening the valve 24^x, holds the valve 37 in position to close the discharge 26^x. When the lever 28 is lowered to close the valve 24^x, the tension on the loop 38^x is relieved allowing the valve 37 to lower and open the discharge 26^x to drain the chamber 9 and generator 10 upon the shutting down of the burner.

In order to control the length of the downward movement of the core 30 and the lever 28, 35 I provide a stop rod 40 slidably held in a guide 41 and having a handle or knob 40^x at its upper end and a turned lower end 40° extending beneath the lever 28 to engage therewith at the downward limit of its stroke and acts as an 40 emergency control to operate burner should electric power fail. This is accomplished by manually pulling knob 40^x up.

The stop rod is secured in position by a sleeve 42 set screwed to the rod and engaging the upper 45 end of the panel 16.

I will now describe the gas control. 43 is a gas supply pipe carried on the panel 16 by a branch pipe 43^x leading through the panel and from which extends a gas pipe 43° leading to a pilot 44 to provide a torch flame. 45 is a gas pipe leading to a pilot 46 of a Bunsen type and which is constantly lit during operation. The pipe 43° is controlled by a valve 47 similar to the valve 24^x, 23' hereinbefore described and is 50 operated by a lever 47^x.

I will now describe the oil feed. 48 is a valve casing provided with a central inlet 49 at its lower end and having a tapered valve seat 50. 51 is a float contained in the casing and carrying a valve pin 52 which extends through the top of the casing and coats at its lower end with the valve seat 50. 53 is a weight carried by the lever 28 so as to engage the upper end of the valve pin 52 and hold the pin in the closed 55 position when the lever 28 is lowered.

54 is the oil outlet pipe provided with a branch 54^x leading from the casing 48 to the oil inlet 14° of the nozzle 14.

Having described the principal parts involved 70 in my invention I will briefly describe the operation of the same.

A gas cock (not shown) is first opened to admit gas to the pipe 43 to feed gas to the pilot burner 46 which is then manually lit. The lever 47^x is 75 then swung down to open the valve 47 and to feed

gas by the pipe 43° to the torch pilot 44 which is lit by the flame of the pilot 46. By means of the torch 44 the chamber 9 is heated to a temperature of 225°. The switch 35 is then closed. The solenoid core 30 is then lifted, provided the circuit is closed at the thermostat 34^x, raising the lever 28 to open the valve 24^x allowing water to flow from the inlet 17 through the preheater 18 and pipe 19 to the pipe 22 and thence through the valve 23, (shown in detail in Fig. 3) to and 10 through the tube 26 and pipe 27 to the generator 10 which, after it is filled and overflows, forms a film of water over the bottom of the chamber 9. This steam, which is dried by passing around the chamber 9, passes through the pipe 15 12^x to the nozzle chamber 14 and is projected through the nozzle 14^x. By the raising of the lever 28 as above described the discharge valve 37 is closed and the float 51 freed by the raising of the weight 53, thus raising the valve pin 52 off 20 its seat and allowing oil to flow through the pipes 54 and 54^x to the nozzle inlet 14° to mix with the steam discharge to be projected against the hot surface of the chamber 9 to be ignited thereby and form a flame which is spread in fan shape 25 by the vanes 55 which also passes through the open centre 9° to be deflected around the top of the chamber 9 by the deflector 56. The valve 47 is then closed extinguishing the torch flame of the pilot 44. 30

By means of the flame from the nozzle 14^x the water in the generator 10 is converted into steam. Some of such steam loaded with moisture passes to the humidifier. The remaining steam passes around the chamber to the outlet 12. The water 35 is fed to the generator 10 at a given pressure and initially fills and overflows the same. Steam is then formed in the chamber 9 building up a steam pressure opposing the water pressure and creating back pressure against the incoming water 40 which controls the necessary water flow to continue an even flow or pressure of steam in proportion to water pressure.

It will thus be seen that a balance is continually sought in the device between water and 45 steam pressure.

From the foregoing it will be seen that I have devised a device in which a motor or other revolving parts are dispensed with rendering the device noiseless and materially reducing the cost 50 of manufacture, in which the feed of water and oil are regulated by a single automatic control, in which the oil is supplied in proportion to the steam pressure through the operation of the lever 28 and solenoid 29, the operation of which 55 is controlled by the thermostat 34^x to supply water and oil to the burner as required by room temperature, in which the heat of the starter and control chamber is maintained by a continuously burning pilot, in which at starting the water may 60 be quickly converted into steam by a separate torch flame ignited by the pilot, in which the water fed to the generator is preheated during its passage thereto, and in which the surplus water is automatically discharged from the generator 65 when the burner is shut down.

What I claim as my invention is:—

1. An open topped steam generator, a water supply duct leading into the generator bottom, a pressure control chamber extending over the open 70 top of the generator, means for heating the generator and control chamber to convert the water into steam, a valve for controlling the water supply, a drain valve in the water supply duct, and means for automatically opening the drain valve 75

on the closing of the water supply valve and for closing the drain valve on the opening of the water supply valve.

2. An open topped steam generator, a water supply duct leading into the generator bottom, a pressure control chamber extending over the open top of the generator, means for heating the generator and control chamber to convert the water into steam, a valve for controlling the water supply, a drain valve in the water supply duct, means for automatically opening the drain valve on the closing of the water supply valve and for closing the drain valve on the opening of the water supply valve comprising an electric circuit, and means energized thereby for operating the water supply and drain valves.

3. An open topped steam generator, a water supply duct leading into the generator bottom, a pressure control chamber extending over the open top of the generator, means for heating the generator and control chamber to convert the water into steam, a valve for controlling the water supply, a drain valve in the water supply duct, means for automatically opening the drain valve on the closing of the water supply valve and for closing the drain valve on the opening of the water supply valve comprising an electric circuit, a solenoid in said circuit, a solenoid core, and means operated by the raising of the core as the solenoid is energized for operating the water supply and drain valves.

4. An open topped steam generator, a water supply duct leading into the generator bottom, a pressure control chamber extending over the open top of the generator, means for heating the generator and control chamber to convert the water into steam, a water supply valve operated by rotation, a lever secured to the rotating part, means for automatically raising the lever to

open the water supply valve in accordance with temperature requirements, a drain valve connected to the water supply duct, and connecting means between the lever and drain valve operated by the raising of the lever for closing the drain valve and for opening the drain valve by the lowering of the lever.

5. An open topped steam generator, a water supply duct leading into the generator bottom, a pressure control chamber extending over the open top of the generator means for heating the generator and control chamber to convert the water into steam, a water supply valve operated by rotation, a lever secured to the rotating part, means for automatically raising the lever to open the water supply valve in accordance with temperature requirements, a drain valve connected to the water supply duct, connecting means between the lever and drain valve operated by the raising of the lever for closing the drain valve and for opening the drain valve by the lowering of the lever, and resilient means incorporated in said connecting means for holding said drain valve to its seat.

6. The combination with an open topped steam generator, a water supply pipe leading into the bottom of the generator, an annular pressure control chamber having an orifice in the bottom thereof in which the open top of the generator is secured, a dividing wall extending between the inner and outer walls and between the top and bottom walls of the control chamber and in proximity to the generator, and a steam outlet leading from the control chamber at one side of the dividing wall adjacent the steam generator and a steam outlet leading from the control chamber at the other side of the dividing wall at a point remote from the generator.

THOMAS HENRY McCUALEY.
